UNITED STATES PATENT OFFICE.

ALFRED B. LEWIS AND WILLIAM J. TAGGART, OF PHILADELPHIA, PENNSYLVANIA;
SAID LEWIS ASSIGNOR TO ROBERT J. TAGGART, OF PHILADELPHIA, PENNSYLVANIA.

SPIGOT.

Application filed August 17, 1921. Serial No. 492,903.

To all whom it may concern:

Be it known that we, ALFRED B. LEWIS and WILLIAM J. TAGGART, citizens of the United States, residing in Philadelphia, Pennsylvania, have invented certain Improvements in Spigots, of which the following is a specification.

Our invention relates to a type of spigot, in which the handle is given a lateral turn 10 to open or close the spigot.

One object of the invention is to simplify the construction of a spigot of this type and to protect the joint between the fixed and movable parts.

15 A further object of the invention is to provide a flange with a stop to limit the movement of the nozzle.

20 A still further object of the invention is to design the spigot so that the parts can be readily assembled.

These objects we attain in the following manner, reference being had to the accompanying drawings, in which:

25 Fig. 1 is a perspective view of our improved spigot;

Fig. 2 is a sectional view showing the spigot in the closed position;

Fig. 3 is a view similar to Fig. 2, showing the spigot in the open position;

30 Fig. 4 is a sectional plan view on the line 4-4, Fig. 2;

Fig. 5 is a detached perspective view of the valve; and

Fig. 6 is a sectional view of the handle.

35 Referring to the drawings, 1 is the body of the spigot shaped as shown in Fig. 1 and having a screw threaded portion 2 and a flange 3. The body of the spigot has a cylindrical section 5 at the opposite end from the screw thread and projecting from the body portion directly above the cylindrical section 5 is a wide flange 6. Within the cylindrical portion is a web 7 having a central passage 8. 9 is an internal screw 40 thread with which engages the thread 10 on the valve carrier 11. This carrier has a projection 12, which extends into an opening in the cross bar 13 cast integral with the nozzle 14, shaped as shown in Fig. 2.

45 50 On the upper end of the valve carrier is a disk valve 15, held in place by a screw 16. This valve 15 bears against a flange 17 surrounding the passage 8 in the web 7. The

nozzle section 14 has a portion 18 which snugly fits the cylindrical portion 5 of the body. Secured to the upper end of the nozzle section is a ring 19 having a handle 20 by which the spigot is turned. The ring is secured to the nozzle by a set screw 21. Depending from the wide flange 6 is a pin 22, which acts as a stop to limit the movement of the valve in either direction, the pin striking the abutment 23 formed in the ring at one end of a slot or recess 24 and an abutment 25 at the opposite end of the slot.

55 60 65 By this construction, it will be seen that we are able to make a very simple spigot, which can be easily operated and one in which the nozzle and the valve can be easily detached for repairs.

70 75 80 By making the body portion with an extended flange, which projects over the nozzle section and the ring, the parts are thoroughly protected from any foreign matter entering the space between the nozzle and the body portion.

85 90 95 The valve carrier 11 is secured to the cross bar 13 of the nozzle 14, consequently, on turning the nozzle in one direction, the valve is withdrawn from its seat and, when turned in the opposite direction, it is forced against its seat. The stop pin 22 limits the movement of the nozzle and prevents the valve carrier being disengaged from the cylindrical section of the nozzle. By adjusting the nozzle in the handled ring, the valve can be taken up for wear.

We claim:

95 100 The combination in a spigot, of a body portion having a depending cylindrical section in which there is a valve seat, said section being smooth on the outside and threaded on the inside; a nozzle section extending over the cylindrical section; a valve carried by the nozzle section and having a screw thread adapted to the thread of the cylindrical section; a ring secured to the upper portion of the nozzle and having an operating handle, said ring being recessed to form stops; and a flange on the body portion extending over the upper end of the nozzle and the ring and having a depending pin extending into the recess of the ring to limit the movement of the nozzle.

ALFRED B. LEWIS.
WILLIAM J. TAGGART.
